John E. Genn

by Burton A. Burton
his Atty.

UNITED STATES PATENT OFFICE.

JOHN E. GENN, OF CHICAGO, ILLINOIS, ASSIGNOR TO STEWART-WARNER SPEEDOMETER CORPORATION, OF CHICAGO, ILLINOIS, A CORPORATION OF VIRGINIA.

INSTRUMENT-BOARD.

1,300,377.

Specification of Letters Patent. Patented Apr. 15, 1919.

Application filed April 6, 1918. Serial No. 226,995.

To all whom it may concern:

Be it known that I, JOHN E. GENN, a citizen of the United States, residing at Chicago, in the county of Cook and the State of Illinois, have invented certain new and useful Improvements in Instrument-Boards, of which the following is a specification, reference being had to the accompanying drawings, forming a part thereof.

10 The purpose of this invention is to provide an instrument board and means for readily securing the same to a vehicle body not so equipped. The invention consists in the features of such board and securing means hereinafter described and shown in the drawings as indicated by the claims.

In the drawings:

Figure 1 is a face view of an instrument board embodying this invention, showing 20 also certain parts of the vehicle body with which it is associated.

Fig. 2 is a detail section taken as indicated at line 2—2 on Fig. 1.

Fig. 3 is a side elevation with respect to 25 the vehicle body showing the board in end elevation and partly in section, and illustrating a form of securing means different from that shown in Figs. 1 and 2.

Fig. 4 is a detail section with respect to the 30 board at a vertical plane adjacent the steering column of the vehicle, illustrating a further modification of means for securing the board in position.

Fig. 5 is a detail section taken as indicated 35 at line 5—5 on Fig. 4.

The vehicle body to which this board is shown as applied includes side sills or panels, 1, surmounted by cowl sides or fittings, 2, which include upstanding brackets, 3, supporting a wind shield, 4. The instrument board, 5, whose primary purpose is to support a speedometer, 6, or other instrument for information of the driver, is formed with end portions, 7, lodged upon the side sills 40 1 and overlapping rearwardly facing downwardly sloping curved surfaces afforded by inturned flanges, 2^a, of the cowl sides, 2, and resting against said surfaces, said end portions, 7, being preferably shaped at their 45 under surfaces to conform to the rearwardly sloping curved surfaces of the cowl sides, 2, as indicated in Fig. 3. A very simple means of securing consists in clamping bolts, 8, shown in Figs. 1 and 2, fitted with specially

formed washers, 9, having tongues of reduced thickness, 10, overlapping the inturned flanges of the cowl sides, 2, against which the end portions, 7, of the board, 5, rest. Additional firmness and neatness of appearance is provided by a groove, 11, in the upper edge 55 of the board, embracing and accommodating the depending flange or edge, 12, of the cowl.

An alternative means of securing is illustrated in Fig. 3, as consisting in a stop pin, 13, driven obliquely but nearly vertically into the short sill or upper edge of the panel, 1, extending immediately rearward from the rear face of the cowl sides, 2, the lower edge of the board, 5, resting upon this short sill, the groove, 11, engaging the cowl 60 edge, 12, and the pin, 13, preventing the lower edge of the board from slipping rearwardly along the sill. If preferred the board may be formed with a groove, 14, merely wide enough to accommodate the pin, 13, and 65 permitting it to be driven entirely beyond the surface plane of the board, as shown in Fig. 3. In the particular vehicle body to which the board is shown as applied, it will be seen that the horizontal sill is very short 70 although the line of the sill is continued in the top edge of the door, 15, immediately to the rear of the panel, 1. The sill is in all cases, however, long enough to provide lodgment for the edge of the instrument board, 80 75 85 5, which is all that is necessary with this means of securing, since the stop pin, 13, is accommodated in the same length of sill which provides said lodgment for the board.

A third mode of securing for the board 90 is illustrated in Figs. 4 and 5, and consists in a clip secured to the steering column, 16, and comprising a band, 17, provided with a clamping bolt, 18, and a plate or lug, 19, overhanging the face of the board, 5.

I claim:

1. In combination with a vehicle body having a cowl with a depending edge extending transversely of the body and side sills in a plane below said edge, an instrument board 100 lodged upon said sills with its upper edge engaging the depending cowl edge, and means positively stopping said board against slipping along said sills.

2. In combination with a vehicle body having a cowl with a depending edge extending transversely of the body, side sills in a plane below said edge, and cowl sides having rear-

wardly facing surfaces sloping downwardly from said cowl edge to said sills respectively, an instrument board lodged upon said sills against said surfaces of the cowl sides with its upper edge engaging the depending edge of said cowl, and means positively holding said board against said sloping surfaces of the cowl.

3. In the combination set out in claim 1,
10 the said stopping means comprising a stop pin inserted in each sill and projecting there-

from proximate to a rearwardly facing surface of the board.

4. In the combination set forth in claim 3, the rearwardly facing surface being the bottom of a groove formed to accommodate said pin below the principal face plane of the board.

15 In testimony whereof, I have hereunto set my hand at Chicago, Illinois, this 30th day 20
of March, 1918.

JOHN E. GENN.
